(57) **CLAIM**

The ornamental design for coalescer filter having baffle plate, as shown and described.

DESCRIPTION

FIG. 1 is a perspective view of a coalescer filter having baffle plate embodying our new design;

FIG. 2 is a front side elevational view thereof, the rear side elevational view being a mirror image;

FIG. 3 is a right side elevational view thereof, the left side elevational view being a mirror image;

FIG. 4 is a top plan view thereof; and,

FIG. 5 is a bottom plan view thereof.
